UNITED STATES PATENT OFFICE.

FREDERICK E. LAMB, OF POTSDAM, NEW YORK, ASSIGNOR OF ONE-HALF TO ROBERT A. LAVERY, OF WAKEFIELD, MASSACHUSETTS.

WASHING-MACHINE.

No. 920,760.

Specification of Letters Patent.

Patented May 4, 1909.

Application filed February 11, 1908. Serial No. 415,456.

To all whom it may concern:

Be it known that I, FREDERICK E. LAMB, a citizen of the United States, residing at Potsdam, in the county of St. Lawrence 5 and State of New York, have invented new and useful Improvements in Washing-Machines, of which the following is a specification.

This invention relates to washing machines, having for its object the production of a simple and effective machine for subjecting the clothes to a boiling operation while in motion, the machine embodying means for affording a thorough and complete circulation of hot water and steam through the clothes and the distribution or spraying of such hot water and steam throughout all the clothes contained in the machine.

With the above and other objects in view, the nature of which will more fully appear as the description proceeds, the invention consists in the novel construction, combination and arrangement of parts hereinafter 25 fully described illustrated and claimed.

In the accompanying drawings:—Figure 1 is a perspective view of a complete washing machine constructed in accordance with the present invention, showing the cylindrical body in position to admit of the insertion or removal of the clothes. Fig. 2 is a vertical diametrical section through the clothes receptacle after said receptacle has been inverted or placed in its operative position. Fig. 3 is a vertical longitudinal section through the machine illustrating the circulation. Fig. 4 is a detail perspective view of the hot water and steam chamber.

The machine contemplated in this invention comprises a main body 1 of suitable dimensions and preferably rectangular in shape, the interior of said body being divided by a vertical partition 2 at a suitable point into a boiler 3 and a dead air or insulating chamber 4. At the top, the body 1 is provided with an outwardly projecting flange or ledge 5. The dead air chamber 4 is closed by a top wall 6 while the remainder of the body above the water chamber or 50 boiler 3 is left open with the exception of a narrow lid section 7 which is hinged at 8 adapting the same to be lifted and thrown back for a purpose which will appear.

In the open top of the boiler or water

chamber 3 is arranged a cylindrical clothes receptacle 9, the same being mounted loosely on a shaft 10 by which said receptacle is supported. The shaft 10 projects outside of the heads on the cylinder, as shown in Fig. 2, preferably passing through centrally arranged stuffing boxes 11 on the cylinder heads, the projecting portions of the shaft extending over the top edges of the opposite sides of the body, as indicated in Fig. 1. These projecting portions of the shaft are 65 journaled in bearings 12 mounted to slide on the flanges 5 and being held in place by bolts 13, which work in slots 14 in said flanges, thereby enabling the cylindrical receptacle to be moved to a limited extent 70 lengthwise of the body 1, the object of which will be explained later.

Extending around the outer surface of the receptacle 9 and concentric thereto is a spray nozzle or conduit 15, made tapering as indicated by dotted lines in Fig. 2, one end of which is relatively small or narrow and provided with an opening 16 adapted to receive a nipple 17 extending inward from the partition 2, said nipple containing one end of an 80 arcuate circulating connection or pipe 18 which is connected with the dead air chamber 4, the opposite end of said pipe 18 being inserted and held in another opening 19 in the partition 2 at a point lower down than 85 the nipple 17, the latter being located at and near the top of said partition 2. From the point where the opening 16 is formed the nozzle or conduit 15 gradually increases in width and at its opposite end where it is expanded to the greatest extent, spray ports 20 90 in the form of perforations are provided in the outer wall of the receptacle 9 whereby the hot water and steam passing through the nozzle 15 is distributed and sprayed downward directly upon the clothes in the receptacle 9, the spray ports being arranged at the top of said receptacle.

Opposite the spray ports 20, the cylindrical receptacle 9 is provided with a perforated door 21 which is hinged at one side as at 22 and provided at the opposite side with a slot 23 adapted to pass over an eye or staple 24 through which a locking pin 25 may be inserted to hold said door closed. In addition to its function as a door, the part 21 acts as a drip plate or discharge for the water through the bottom of the cylinder when the

same is reversed from the position shown in Fig. 1 to the position shown in Fig. 3, the latter being the opposite position.

In the bottom of the compartment 3 there is arranged a hood 26 which in connection with the bottom of the body 1 forms a hot water and steam chamber 27 which gradually slopes from one end to the other. This hood is provided at its shallow end with a plurality of drain holes 28 while at the opposite or larger ends said chamber is provided with a projecting nipple 29 which is received in the adjacent lower end of the circulating connection or pipe 18 as clearly shown in Fig. 3.

30 designates a drain cock for drawing off the water of the machine.

The shaft 12 is provided within the clothes receptacle 9 with a dasher or stirrer which may consist of one or more arms 31 projecting rearwardly from the shaft and, if desired, formed integrally therewith as shown in Fig. 2. The shaft is also provided at one end with an operating crank or handle 32, whereby said shaft may be turned for the purpose of rotating the dasher or stirrer within the cylindrical clothes receptacle, the latter being held stationary.

To place the clothes in the receptacle 9, the hinged lid 7 is swung upward and the receptacle 9 is moved toward said lid until said receptacle is disconnected from the circulating pipe 18. The receptacle 9 is then turned until the door 21 is at the top. After placing the clothes in the cylinder, the door is closed and fastened in the manner described. The cylinder is then turned through half the revolution or reversed so as to carry the door 21 which constitutes a drip plate to the bottom. This brings the opening 16 into alignment with the nipple 17 and the receptacle 9 is then slid toward the nipple until an engagement is effected after which the lid 7 is swung downward to its closed position where it acts as a back stop for the receptacle 9. In this position the spray ports 20 are disposed at the top of the receptacle. The machine as a whole is placed over the fire and

the necessary amount of water introduced into the chamber 3. This water finds its way into the hot water or steam chamber 27 and when sufficiently heated to produce steam, such steam combined with hot water is forced through the circulating connection 18 into the concentric spray nozzle 15 and then through the spray ports 20 upon the clothes, the latter being kept in motion by the dasher or stirrer 31. After passing through the clothes, the water finds its way out through the drip plate or door 21 and in a comparatively cool condition falls into the compartment 3, passing from there into the chamber 27 where it is again brought to the boiling point. In this way a complete circulation of steam and hot water is maintained in the machine.

I claim:

1. A washing machine comprising a boiler, a reversible clothes receptacle mounted therein, a shaft on which said receptacle is supported, mounted in slide bearings on the boiler, a circulating connection communicating with the boiler and having a detachable engagement with said clothes receptacle, a dasher or stirrer on said shaft, working within the clothes receptacle, and a movable stop for holding said clothes receptacle in engagement with the circulating connection.

2. A washing machine comprising a boiler, a cylindrical clothes receptacle reversibly mounted therein, a perforated plate having a jointed connection with one side of said receptacle, a spray nozzle communicating with the opposite side of said receptacle and mounted thereon, a dasher or stirrer working in said receptacle, and a tapering circulating connection communicating with the boiler at one end and communicating with said nozzle at the other end.

In testimony whereof I affix my signature in presence of two witnesses.

FREDERICK E. LAMB.
